UNITED STATES PATENT OFFICE.

WILLIAM TUTTLE, OF DOWAGIAC, MICHIGAN.

AIR-HEATING STOVE.

SPECIFICATION forming part of Letters Patent No. 354,994, dated December 28, 1886.

Application filed December 15, 1885. Serial No. 185,708. (No model.)

To all whom it may concern:

Be it known that I, WILLIAM TUTTLE, a citizen of the United States, residing at Dowagiac, county of Cass, State of Michigan, 5 have invented a new and useful Air-Heating Stove, of which the following is a specification.

This invention relates to that class of stoves which have air-passages between the fire-box and the exterior inclosure or jacket of the 10 stove; and it has for its object certain improvements below described and claimed.

In the drawings forming a part of this specification, Figure 1 is a vertical section on line 22 in Fig. 3; Fig. 2, a vertical section on line 15 33 in Fig. 4; Fig. 3, a cross-section on lines 00 in Figs. 1 and 2; Fig. 4, a cross-section on lines 11 in Figs. 1 and 2; and Fig. 5 is a side view, looking from a point at the left hand of Figs. 2 and 4, with portions of the stove broken 2c away, showing a change in construction, hereinafter described.

Referring to the letters marked on the drawings, B is the interior fire-place of the stove, the lower part of which is ordinarily termed 25 the "fire-box;" but for convenience of description I shall term the whole fire-place B the "fire-box."

The ordinary grated bottom is shown at u. The front draft is shown at c', the door at v, 30 the rear damper or draft at c, the stove-base at F, and P is the ash-pit.

The two walls C D, having a heat-space, r, between them, constitute the exterior inclosure of the stove, leaving a vertical air-passage, A, 35 on both sides of the fire-box B, between said fire-box and inclosure.

The well-known object of the air-passages A A is to allow the air to circulate from below the stove up through the passages and out 40 into the room at the openings at the top of the stove. (See the arrows in these passages A A in Fig. 2.) If the stove were provided with simply the wall C, ordinarily termed a "jacket," the air in the passages would be heated 45 only by the radiation from the heated surface of the fire-box wall, and the wall C would be comparatively cool or contracted with the wall D in my construction, which is heated by the fire and heat entering the heat-space r between 50 the walls C D. Furthermore, the wall C is also heated by the fire and heat in said heat-

spaces, for which reason the air in the passages A A receives an additional heat. Of course the outer wall, D, surrounds the stove, Fig. 4, while the walls C inclose the air-passages on the sides of the fire-box. 55

The fire-box, near the top, is provided with a partition, a, separating the heat-space r from the fire-box, the angled part being perforated at t, and provided with a damper, e, 60 to regulate the draft of the fire-box, Fig. 1.

The arrows in the heat-space r in the different figures show the course of the heat and smoke.

The design is that when the fire is first made 65 the draft c' is left open and the draft c closed. When the fire gets to burning, the draft will be largely direct, as indicated by the arrows in the fire-box in Fig. 4; but when the fire is under good headway the draft c' is closed and 70 the draft c opened, when the draft will be what I term a "return-draft," as shown by the arrows in the fire-box in Fig. 3, the fire and heat then all entering the heat-space r, as shown by the arrows in said space in Figs. 3 75 and 4.

Of course the drafts and dampers may be arranged to produce different results and degrees in the draft, as desired and which use may suggest. 8c

I should have stated that the heat-spaces r do not communicate with each other on the back end of the stove until they get above the damper e, as the drawings show. These heat-passages r are only on the sides of the fire-box, the ordinary air-passage being between said passages and the fire-box, and the forward end of the heat-passages r opens into the fire-box, said open end receiving the heat, as before explained, when draft c' is closed and 90 draft c is open. The heat-spaces may be provided with a bridge or partition, R, as in Fig. 5, to retard the passage of the heat, if desired. In this use the door v would be at the opposite end of the stove, and the course of the 95 heat is shown by arrows in Fig. 5. The partitions R are approximately vertically central in the space or passage, and are preferably at an oblique angle. They serve as deflectors to the rising heat, retarding the passage of the same, 100 causing it to be longer in passing throughout the passages to the draft-pipe.

Having thus described my invention, what I claim as new, and desire to secure by Letters Patent, is—

In an air-heating stove, the combination of
5 a fire-box, a wall on each side, inclosing, in conjunction with the fire-box wall, an air-space leading vertically through the stove, and an outer wall encircling the stove and separated from the outer wall of the air-spaces, forming
10 heat-passages on the sides of the stove only, the lower portion of the rear end of the heat-

passages being closed from the fire-box and the other end of said passages opening into the fire-box, substantially as set forth.

In testimony of the foregoing I have here- 15
unto subscribed my name in presence of two
witnesses.

WILLIAM TUTTLE.
